UNITED STATES PATENT OFFICE.

JONAS NORTHROP, OF HOPEDALE, MASSACHUSETTS, ASSIGNOR TO HOPEDALE MANUFACTURING COMPANY, OF MILFORD, MASSACHUSETTS, A CORPORATION OF MASSACHUSETTS.

PICKER-STICK PARALLEL MOTION.

Application filed April 7, 1923. Serial No. 630,514.

To all whom it may concern:

Be it known that I, JONAS NORTHROP, a citizen of the United States, residing at Hopedale, in the county of Worcester and

5 State of Massachusetts, have invented certain new and useful Improvements in Picker-Stick Parallel Motions; and I do hereby declare the following to be a full, clear, and exact description of the invention, such as will enable others skilled in the art to which it appertains to make and use the same.

The present invention relates to an improvement in picker stick parallel motions.

15 The object of the invention is to reorganize and improve these motions in order to render them stronger and more durable, and to these ends the invention consists in the improvement hereinafter described and particularly defined in the claim.

In the accompanying drawings illustrating the preferred form of the invention, Fig. 1 is a front elevation of the parallel motion; Fig. 2 is a section taken on the 25 line 2—2, Fig. 1; Fig. 3 is a section taken on the line 3—3, Fig. 1; and Fig. 4 is a perspective view of a clamp plate hereinafter referred to.

The illustrated embodiment of the invention is described as follows: The stand 10 is secured to the lay rocker shaft 11, provided on its upper side with the rocker surface 12 upon which the sole or rocker 13 of the shoe 14 is supported. The stand is pro-

25 vided with the usual tongue 15 which is received in a tongue slot 16 in the sole of the shoe. The picker stick 17 extends down through a hole in the shoe and is attached by means of the strap 18 to the end of a 40 spring 19, which normally tends to pull upon the strap so as to move the picker stick to the position illustrated in Fig. 1. The shoe is provided with a housing 20 which rises from the sole and partially encloses the

45 picker stick just above the sole of the shoe. A tongue 21, having flanges 22, is supported in the housing of the shoe and engages the edge of the picker stick, the flanges fitting the sides of the stick, and the flat surface 50 of the tongue engaging the edge of the stick. This tongue takes against the wedge-shaped bearing plug *p*. A picker stick bolt 23

passes through the housing 20, the tongue 21, the picker stick 17 and the end of the strap 18, and holds the picker stick on the 55 shoe.

So far as described the construction is that illustrated in the Boisvert Patent No. 775,890, dated November 22, 1904. The bolt 23 after passing through the strap, passes 60 through a hole 24 in the follower piece 25, and is provided with a lock washer and a nut. By tightening up this bolt the picker stick is held in fixed relation to the shoe.

Under the strains to which the parallel motion is subjected in use it has been found 65 that the picker stick is frequently broken at this bolt hole, and the specific object of the present invention is to redesign the construction in such way as to render the stick 70 more durable by affording it more secure and firm connection with the shoe, reinforcing it at its place of liability to breaking. To this end the follower piece 25 is provided 75 with wings 26 on each side, which extend along both sides of the picker stick and are provided with holes 27 for auxiliary bolts 28. The housing 20 of the shoe is provided with lateral ears 29, which extend outwardly beyond the flanges 30 of the housing, and 80 are provided with holes 31 to receive the bolts 28. By means of these bolts an a' led pressure is brought to bear on the parts 85 which embrace and compress the picker stick so as thereby to strengthen the stick at the point where it is most liable to break.

It will be observed that the follower piece 25 is elongated lengthwise of the picker stick, and by means of the three bolts by which it is secured to the housing of the 90 shoe it is pressed against the picker stick with great pressure, the latter being thereby reinforced and strengthened by the follower.

Having thus described the invention, what 95 is claimed is:

A picker stick parallel motion having, in combination, a stand, a picker stick, a shoe, a strap and spring connected with the picker stick tending to return it to outward position, the shoe being provided with a housing, a tongue between the picker stick and housing, a follower piece having portions 100 extended longitudinally along a considerable

length of the picker stick, the end of the strap being extended between the follower piece and the edge of the picker stick, a bolt extending through the follower piece, the strap, the picker stick, the tongue and the housing for clamping the picker stick in place, and two additional bolts, one on each side of the picker stick, said follower piece being provided with wings and said housing being provided with ears to receive said bolts, which act as supplemental means for clamping the picker stick strap and shoe together.

JONAS NORTHRUP.
